[57] CLAIM

The ornamental design for a fitting mirror, as shown
and described.

DESCRIPTION

FIG. 1 is a front elevational view of a fitting mirror
showing my new design;

FIG. 2 is a rear elevational view of the mirror;

FIG. 3 is a right side elevational view thereof, the oppo-
site side being a mirror image;

FIG. 4 is a top plan view of the fitting mirror; and

FIG. 5 is a bottom plan view of the mirror.
